UNITED STATES PATENT OFFICE.

JOHN ELLBERG, OF NEW YORK, AND MAGNUS CRONWALL, OF BROOKLYN,
NEW YORK.

VACUUM TANK

Application filed August 22, 1928. Serial No. 301,236.

This invention relates to vacuum tanks for feeding liquid fuel to internal combustion engines and has for its primary object to provide an improved simplified construction for devices of this character to render them more durable in service, more effective in operation and more sensitive in action. 5

fluid within discharge chamber 12. The lower end of discharge pipe 15 is provided with a port opening 16 with an upwardly presented valve seat for seating a valve 17 which is preferably formed at the lower end of a reciprocatory rod 18. It will be seen from 60 an inspection of the lower portion of Fig- 85

More particular objects of the invention will appear in the specification in connection with certain details of construction referred to in the appended claims.

In the drawings which exemplify our invention in the preferred embodiment somewhat similar to that shown in our copending application Serial No. 260,684 which was filed under date of March 10, 1928, 15 chamber 11. The reciprocatory rod 18 is slidably supported by a strap 19 and has its upper end provided with a conical valve 20 which reciprocates in a valve chamber 21 to and from a valve seat 22 for controlling 70

Figure 1 is a vertical section of a vacuum fuel feed tank constructed in accordance with the principles of our invention, parts being shown in elevation; a port opening 23 which leads from the valve chamber 21 to a vacuum pipe 24. An air inlet chamber 25 provided with a port opening 26 is provided with a ball valve 27

Figure 2 is a similar vertical section of the upper portion of Figure 1, parts being shown in elevation; which is normally seated against a valve seat 75 28 when the valve rod 18 is in its lower position as shown in Figure 1. The valve seat

Figure 3 is an enlarged section on the line 28 is made of suitable size to permit the valve 27 to be engaged by the conical sur-

35 Suitable means for reciprocating the rod 18 may be provided as follows. Float 28 is 90
ble openings in the flanges 5 and 6 of the top and bottom members which are secured by means of nuts 7 threaded to the opposite ends of tie rods 4. A transverse partition 8 is suspended from the cap 2 by means of rods 9, at least one of said rods being provided with a tubular bore 10 for admitting air below the partition 8 and thus placing liquid below said partition under atmospheric pressure. Said partition 8 divides the vacuum tank into an upper receiving chamber 11 and a lower delivery chamber 12. A hermetic seal may be formed around the periphery of partition 8 within the cylindrical wall 1 by means of an annular packing 13. Leading to the inlet chamber 11 is an inlet pipe 14 for fuel, an outlet pipe 15 being secured to the under surface of partition 8 and depending therefrom with its lower end submerged in the

pin 40 to the upper end of double link 41. Said link 41 is pivotally mounted at its lower end on a pin 42 carried by laterally-spaced lugs 43 which are presented upwardly from the top wall of float 28. The link 41 is preferably constrained to reciprocate in a straight line extending through the axis of pin 42 and for this purpose carries a pair of guide rollers 44 which run in the guide 10 slot 30 in the fixed support 29. Mounted on the spring rod 37 between the cross-piece 38 of yoke 32 and the strap end 39 of the lever arm 32, is a compression spring 45 which imparts a tendency to retain the lever arm 32 in raised position as shown in Figure 1 or in lowered position as shown in Figure 2. A discharge pipe 46 leading from the lower chamber 12 has its intake end arranged at a higher level than the discharge opening 16 20 in the pipe 15 and thus maintains a fluid seal at the bottom of pipe 15.

With the parts in their relative positions shown in Figure 1, a relatively low level of the fluid in receiving chamber 11 has permitted the float 28 to fall, thus causing the rod 18 to drop into its lower position. This action opens the vacuum port 23 at the same time that the outlet 16 into the delivery chamber 12 is closed. This movement permits the ball valve 27 to be pressed to its seat and thus prevents the admission of air through the air inlet chamber 25. The resulting partial vacuum in chamber 11 produces an inflow of fuel through the pipe 14. 35 As the fluid level rises in chamber 11, the float 28 elevates the pivot 40 of spring rod 37 until the compression spring 45 becomes suitably disposed to force the lever arm 32 downwardly. This movement produces a 40 rapid upward displacement of the rod 18 to close the vacuum port 23 while at the same time opening the discharge outlet 16 and forcing the ball-valve 27 from its seat. This operation breaks the partial vacuum in 45 chamber 11 to interrupt the inflow of fuel from pipe 14 and permits a recharging of delivery chamber 12 until a subsequent drop of the float 12 causes a repetition of the action just described.

50 We claim:

1. In a vacuum fuel-feed tank having fuel inlet, fuel discharge, air inlet and vacuum openings, the combination with a reciprocatory rod for controlling said openings, of a pivotally mounted lever movably connected to said reciprocatory rod, a float reciprocable on and relatively to said rod, a link connected to and actuated by said float, means for constraining the movement of said link, 55 and a yieldable connection between said link and said lever, said yieldable connection comprising a spring rod movably connected to said link and movably engaging said lever, and a spring mounted on said spring rod and transmitting pressure between said

link and lever for imparting a bias to said lever tending to retain said reciprocatory rod in either of its extreme positions.

2. The combination with a tank provided with fluid-receiving and fluid-discharging chambers provided with a communicating passage, said fluid-receiving chamber being provided with a vacuum-control passage, of a reciprocatory valve rod adapted to alternately close said passages, a lever pivotally mounted intermediately of its ends, one arm of said lever being movably connected to said reciprocatory rod, a float reciprocably mounted on said reciprocatory rod, said float being reciprocable with and relatively to said reciprocable rod, a fixed guide, a link pivotally mounted on said float and movably engaging said fixed guide, and an articulating yieldable connection between said link and the other arm of said lever, and a spring interposed between said abutments on said spring rod.

3. In a vacuum tank, the combination with a reciprocatory rod for controlling the flow of fluid between the receiving and fluid-discharging chambers as well as a communicating passage to a vacuum duct, of a float reciprocably mounted on said reciprocatory rod, an air-inlet valve arranged to be operated by said reciprocatory rod, a lever pivotally mounted on an axis outside of said reciprocatory rod and having one arm thereof movably connected to said reciprocatory rod, the other arm of said lever being presented away from said reciprocatory rod, a fixed guide, a link articulately connected to said float and movably engaging said guide, and a yieldable connection extending between said link and said other arm of said lever.

4. The combination with a tank provided with a fluid-receiving chamber having a valve seat through which fluid is passed and a vacuum-control valve-seat coaxial with the first-mentioned valve-seat, a reciprocatory rod provided at opposite ends with valves adapted to seat on said valve-seats alternately, a pivotally mounted lever having one arm movably connected to said reciprocatory rod and the other arm thereof provided with a spring abutment, a float reciprocable with and relatively to said reciprocable rod, a link pivotally mounted at one end on said float, a spring rod pivotally connected to the other end of said link and having a spring abutment adjacent to that end, the other end of said spring rod being reciprocably mounted in the first-mentioned abutment on said other arm of said lever, and a spring interposed between said abutments on said spring rod.

5. The combination with a tank provided with a fluid-receiving chamber, of a reciprocatory rod adapted by its movement in one direction to control a fluid outlet leading

from said chamber and by its movement in the opposite direction to control an exhaust outlet leading to a vacuum chamber, a pivotally-mounted lever having one arm movably connected to said reciprocatory rod and the other arm thereof provided with a spring abutment, a float reciprocably mounted on said reciprocatory rod and reciprocable relatively to said reciprocatory rod, a link pivotally connected to said float, a spring rod pivotally connected at one end to said link and having its other end slidably engaging said abutment, and a compression spring interposed between said abutment and the pivoted end of said spring rod.

6. The combination with a tank provided with a fluid-receiving chamber, of a reciprocatory rod adapted to control the admission and discharge of fluid, a lever pivotally mounted on a fixed axis and having one arm thereof movably connected to said reciprocatory rod, the other arm of said lever being provided with a spring abutment, a float reciprocably mounted on and relatively to said reciprocatory rod, a link pivotally mounted at one end of said float and having its other end constrained to move in a predetermined path, a spring rod pivotally connected at one end to said link and having a spring abutment adjacent to that end, the other end of said spring rod being reciprocably mounted in the first-mentioned abutment, and a spring interposed between said abutments and on said spring rod.

7. The combination with a tank provided 35 with fluid-receiving and fluid-discharging chambers and having a valve-seat through which fluid is passed from one of said chambers to the other, said fluid-receiving chamber being provided with a vacuum-control 40 valve-seat coaxial with the first-mentioned valve-seat, a reciprocatory rod provided at opposite ends with valves adapted to seat on said valve-seats alternately, an air-inlet valve arranged to be opened by said reciprocatory rod on its movement toward said vacuum-control valve-seat, a fixed support, a lever pivotally mounted on said fixed support and having one arm thereof movably connected to said reciprocatory rod, the 50 other arm of said lever being provided with a spring abutment, a float reciprocably mounted on said reciprocatory rod, said float being reciprocable with and relatively to said reciprocable rod, a fixed guide, a link 55 pivotally mounted at one end on said float and having its other end movably engaging said fixed guide, a spring rod pivotally connected at one end to said link and having a spring abutment adjacent to that end, the 60 other end of said spring rod being reciprocably mounted in the first-mentioned abutment on said other arm of said lever, and a spring interposed between said abutments on said spring rod.

JOHN ELLBERG.
MAGNUS CRONWALL.
